STORAGE CABINET FOR CONTACT LENSES

Harold V. Jones, 120 N. Walnut St., Champaign, Ill.

Filed July 19, 1960, Ser. No. 61,429

Term of patent 14 years

(Cl. D80—11)

Fig. 1

Fig. 2

Fig. 3

FIG. 1 is a front elevational view of a storage cabinet for contact lenses showing my new design;

FIG. 2 is a right end elevational view thereof;

FIG. 3 is a top plan view thereof;

FIG. 4 is a front perspective view taken from the top thereof with the cabinet in an open position;

FIG. 5 is a top plan view thereof as shown in FIG. 4; and

FIG. 6 is an enlarged vertical cross-sectional view thereof taken on line 6—6 of FIG. 4.

I claim:

The ornamental design for a storage cabinet for contact lenses, substantially as shown.
